HYDRAULIC DRIVING MEANS FOR WINDING
AND ROLLING MACHINES

Arthur Spencer and John Hewitt, London, England, assignors to Vickers-Armstrongs Limited, London, England, a British company

Application March 3, 1948, Serial No. 12,848
In Great Britain March 19, 1947

4 Claims. (Cl. 80—32)

1

This invention relates to hydraulic rolling machines for rolling metal and metal alloy strips or stock by feeding the material between rolls from one drum to another, the material being drawn between the rolls of the mill when passing from one drum to the other, so that in one direction of operation one of the said drums acts as a coiler-on drum and the other as a coiling-off drum. An object of the present invention is to provide a reversible mill for rolling metal strips or stock having a hydraulic pump serving a motor for each drum and providing independent hydraulic drive therefor so that it is possible to operate any single drive to facilitate threading in of the work.

Another object of the present invention is to ensure maintenance of the operative pressure across each pump and motor and the compensation for changes in diameter of the coil buildup to be made by adjusting the stroke of the hydraulic unit.

Another object of the present invention is to provide a mill in which the pressure on the work is governed by a servo unit and thereby obviate the disadvantages of relying upon pressure release valves for this purpose.

Another object of the present invention is to provide in conjunction with a reversible hydraulic rolling mill means which responds accurately to a signal from the pressure side across each pump and associated motor to correct the strokes of the motors to maintain in such motors a constant pressure and in which the said means has a derivative control which reduces any tendency for the hydraulic pressure to surge and further acts on the strokes of the motors to give a predetermined torque output for each motor.

Another object of the present invention is to provide a rolling mill in which the speed of the strip adjusts itself automatically to the process by reason of the fact that the torque cannot be applied until there is a re-action of the process.

A still further object of the present invention is to provide a reversible rolling mill in which, in addition to the means driving the rolls there is provided a pair of hydraulic pumps with a common prime mover driving them, and a pair of variable stroke hydraulic motors individually distinctively associated with the said pumps in a manner which affords a closed hydraulic circuit across each pump and its associated motor so that, by reason of the connection of the stock or material across the two drums, one of the drums can act as a coiler-on and the other as

2

a coiler-off and this condition reversed at the end of a rolling operation, and in which the coiler-off drum transmits the tension in the material across it and the rolls to its motor to feed back part of the power generated to the said prime mover, and to combine therewith fluid pressure actuated means to increase the stroke of the coiling-on drum motor as the coil diameter increases so as to increase the torque applied to said drum and to maintain a substantially constant horse power in the motor driving said drum.

In addition to the foregoing, an object of the present invention is to control the stroke of the hydraulic motors positively by a pair of hydraulic fluid pressure actuated drivers having a source of operative fluid pressure distinct from that in the closed circuits of the pumps and motors. That is to say, there is a positive fluid pressure actuation of the drivers varying the strokes of the motors both for increasing and decreasing the strokes of the motors.

In order that the invention may be clearly understood and readily carried into effect diagrammatic drawings are appended hereto illustrating embodiments thereof, and wherein:

Figure 1 is a diagrammatic view showing a mill with three hydraulic drives to (a) rolls, (b) coiling-off drum, (c) coiling-on drum. Each drive consists of a hydraulic pump and motor the hydraulic pumps being driven by electric motors or any other prime movers. This figure also shows a modified method of obtaining the desired correction for change in tension in the strip when a highly sensitive response to change is necessary.

Figure 2 is a diagrammatic view showing the complete hydraulic circuits of one arrangement of control unit for obtaining the control of the hydraulic motor horse power in the coiling drums.

Figures 3 and 4 are detail views showing a modification of the phase advance or error-derivative part of the appliance.

Referring to Figure 1 of the drawings showing a mill operated by hydraulics, there are shown three hydraulic drives each hydraulic system consists of a variable stroke pump feeding a hydraulic motor. In this case the three hydraulic pumps as shown are driven by two electric motors, one motor 100 driving the pump for the main mill drive and the other motor 113 fitted with shaft extensions at both ends driving the two pumps operating the coiling on and coiling off drives, but may be driven by a single motor through gears or by any other form of prime mover.

The pump 101 for the roll drive has a variable stroke and controls the speed of the hydraulic motor 102 which has a fixed stroke. The coiling drum pumps 103 and 103' also have variable stroke, these are coupled together with the stroke of the mill pump 101 through shafts and gears 104, 105, 106 and 107 to handwheel 108 so that the delivery of all three pumps have the same ratio at all speeds of the mill. The hydraulic motors 109 and 109' for both the drums 110 and 110' have variable stroke. The strokes of the hydraulic motors 109 and 109' are positioned by control units 110a and 110b through linkages 111, 120, 121, 122 and 123, or 111', 120', 121', 122', 123'. Assume the strip or other material being dealt with is passing from left to right of the mill as depicted in Fig. 1. Drum 110 coiling off and drum 110' is coiling-on. When rolling heavy gauge metal and under like conditions in which there is not likely to be any appreciable change in the high pressures required to operate the motors 109 and 109' or in which the change in such pressures will not produce any great change in the effect in the heavy gauge metal, the control units 110a and 110b are connected to the pressure system through pipes 112 and 112'. However, when dealing with quite thin gauge metal strip, e. g. of a foil-like nature, and other materials which are very susceptible to change in tension, it is desirable to connect the control units 110a and 110b to a constant pressure source which feeds the units at pressures controlled by the tension in the material, as hereinafter described with reference to the devices A and B of Figure 1. The pipes connected to the units 110a and 110b in this case are indicated at 112a and 112b. Handwheels 113 and 113' are for setting the spring which will determine the operating pressure in the pipes 114 and 114' between the hydraulic pumps 103 and 103' and hydraulic motors 109 and 109'. The pipes 114, 114', 115, 115', 116 and 116' connect the hydraulic pumps 101, 103 and 103' to the hydraulic motors 102, 109 and 109'.

The foregoing describes the arrangement of a reversing mill where each coiling drum reverses its operation, i. e. from off coiling to on coiling or on coiling to off coiling according to the direction of the strip passing through the rolls 117. The horse power input to coiling motors 109 and 109' will depend upon the speed of the strip and the tension in the strip which is equivalent to the quantity of fluid and pressure circulating through the motors 109 and 109'. Therefore since the quantity of fluid can be made to vary as the strip speed, by virtue of the fact that the handwheel 108 controls simultaneously the stroke mechanism of the three pumps 101, 103 and 103', a control of pressure in the coiling motor system will give a control of tension in the strip.

The control units 110a and 110b are designed to give a constant pressure in the pipes 114 and 114' feeding the motors 109 and 109', see description of Figure 2. When the pressure in the coiling-on motor 109' rises due to the increase of coil diameter, the control 110b will move lever 111' to increase the stroke of the motor 109' and give out a greater torque at a slower speed, until the pressure has been restored to the predetermined setting to suit the required tension.

Meanwhile, the coiling-off control unit 110a operates in the opposite direction. The coiling-

off drum 110 has to give a resistance to the pull of the rolls 117, and for this drive the hydraulic motor 109 is being driven by the rolls 117 via the strip and drum 110. Therefore part of the power is regenerated back into the electric motor 108 as the hydraulic motor 109 is acting as a pump and the hydraulic pump 103 is acting as a fixed stroke motor. When the drum diameter is reduced by the uncoiling of the strip, the pressure in pipe 114 tends to increase because owing to the increase in speed the motor 109 is delivering a greater quantity of fluid than that corresponding to the capacity and speed of pump 103 and in this case control unit 110a will decrease the stroke of motor 109 so that the pressure is maintained at the higher drum speeds.

It will be seen that the control 110a operates in a reverse direction when uncoiling, i. e. the pressure increase, in this case in pipe 114, tends to decrease the stroke. The aforesaid couplings between the control units 110a and 110b have reversing linkages with the appropriate motors operated by handlevers 119 and 119' which have to be changed at the end of the pass for the next pass to be taken in the reverse direction. For example, the hand lever 119 by moving frame 120, determines whether control unit shaft 124 moves stroke lever 111 in clockwise or anti-clockwise direction i. e. the position of the block 123 in the slot of frame 120 determines whether the pull-push movement of the control box shaft 124 is operating through link 122 or 121 to top or bottom of lever 111.

It will be obvious that the above considerations apply where material such as strip or wire is being pulled through rolls or dies by the coiling on drum from the coiling off drum without an intermediate drive. In such a case the whole power is provided by the coiling on drive the coiling off drive providing back tension as required. The apparatus employed is the same as that described and depicted in Figure 1 with the deletion of main drive pump 101 and hydraulic motor 102.

Referring to Figure 2 of the drawings the aforesaid hydraulic power unit can be regarded as the hydraulic motor 109' aforesaid in which the stroke of the pistons operating in the cylinders is adjusted by controlling the lever 111' of the stroke control or tilting member from the control unit 110b which embodies servo means responsive to differences in tension and/or rate of travel of the material from the supply source to the take-up means, the hydraulic motor being connected to a pump 103' driven at a predetermined speed. The motor 109' is preferably of the swash plate type.

The servo device aforesaid embodies a sliding type of pilot valve 4 operated off a system of linkage and controlling the admission of pressure fluid to a cylinder 5 accommodating a piston 6 having a push-pull connection 124' to the actuating lever 111' of the tilting plate of the motor 109' the piston rod 8 extending through both ends of the cylinder, the end remote from the motor sliding in a cylindrical chamber 9 acting as a dash-pot device and accommodating midway between its ends a needle type bleed valve 10 together with means (hereinafter described) for adjusting the reaction of the dash-pot to the movement of the piston, the arrangement being such that when the piston 6 is moved to adjust the tilt of the plate of the motor 109' suction or pressure according to the direction of movement

of the piston 6 is created in the dash-pot 9, and the piston 11 of the dash-pot is moved against the influence of a leaf spring 12 further into or away from the cylinder, the dash-pot piston being connected by a link 13a to the leaf spring 12, which link is connected about midway between its ends to one end of a relatively perpendicular lever 14, e. g. as shown, its upper end, which by reason of the traction of the dash-pot piston, applies through the medium of a connecting rod 15, sliding movement to the pilot valve. The lower end of this lever 14 turns about the upper end of a further lever 16 controlled through the medium of a rod 17 from a flexible diaphragm 18 supported at its perimeter in a pocket 19 in such manner that variations in pressure in the pocket will produce a movement of the aforesaid rod 17 and consequently adjustment of the lever 16 by reason of the pivotal connection 16' of the rod 17 to the lever 16. The lever 16 actuated off the diaphragm can, for the purpose of designation be regarded as the "diaphragm actuated" lever, the first mentioned lever which is connected to the pilot valve being suitably designated as the "dash-pot actuated" lever.

The diaphragm 18 with its pocket 19 forms part of a stabilising device comprising an outer housing or block 20 within which slides a cylindrical inner block 21 having a quite restricted movement relatively to the outer block and being damped by a dash-pot 22 in one end of the outer block, the piston 23 of this dash-pot being formed on the end of a rod 24 remote from the inner block and carrying between its ends a double-piston type of valve 25 operating in a chamber 25' fed by a conduit 26 leading from the aforesaid pocket 19 and having a port 27 to exhaust, this pocket 19 also communicating with a bore 28 in the end of the aforesaid outer block remote from the end containing the dash-pot, this bore receiving a double-piston type of valve 29 connected by a rod 30 and link 30' to the upper end of a further lever 31 the fulcrum 32 of which is midway between its ends, the lower end of this third lever being connected by a link 33 to an abutment member 34 of a spring 35 of a pressure measuring device, comprising the plunger 36 carried by the abutment 34 and operating within a cylinder 37, which when rolling heavy gauge metal as mentioned hereinbefore, can be connected by a conduit 112' to the feed line 114' from the pump 103' to the motor 109'.

However, when winding or rolling the thin gauge materials, such as metal foil, or even plastic materials having a relatively high yield to tension in which relatively low pressures are employed it is necessary to connect the conduit 112' to a source of pressure independent of the feed line 114', and in which the pressure applied to the cylinder 37 is controlled from the tension of the material being wound on to or off from the drum 110'. Hence, in Figure 1 there is shown at A and B floating bearings 80 and 80' for the drums 110 and 110', each bearing being fixed to a plunger 81 operating in a cylinder 82 to which is connected a pipe 83 connected to the pressure side of a constant capacity pump (not shown). The pressure from this pump is fed into the cylinder 37 via line 112b (or 112a) and as the tension in the drum 110' builds up against the pressure in the cylinder 82 a release port 84 leading by line 85 to a tank in the circuit of the latter mentioned pump is gradually throttled down, and the resulting pressure obtained by this throttling down is fed into line 112b to the cyl-

inder 37 and the tilt of the lever 111' thereby constantly adjusted to take care of any tendency for the tension in the material to change.

The said bore 28 accommodating the latter mentioned double piston type of valve 29 communicates with the inlet 4' of the cylinder 4a of the aforesaid pilot valve via a pipe line 40' leading from the discharge 41' of a gear pump 41 (driven from an electric motor 42) and a branch line 40a. This motor 42 would normally be a fractional horsepower motor.

An adjusting screw 58 is provided to enable the loading of the spring 35 to be varied, the screw 58 being operated via worm gear 59 driven from a tension adjustment shaft 60, and the aforesaid spring 35 is interposed between the said abutment 34 and one end of a housing 43 and connected by suitable remote control means, e. g. a cam or link and lever 44 and shaft 45, to a tension indicator 46 to indicate the pre-setting load on the spring. The shaft 42' on the aforesaid low horsepower electric motor 42 to the gear pump 41 has a gear connection 42a to a shaft 47 driving an eccentric 48 operating a longitudinal rod 49, the end of which remote from the eccentric is connected to the lower end of a link 50 pivoted at its upper end to a fixed pivotal point 51 thus providing a "dither" mechanism to keep the whole of the mechanism of the control apparatus "alive" and thus remove static friction. This ensures that the pilot valve 4 will accurately return to its closed position when no pressure error exists, and will thereby eliminate any tendency for the tilt control piston 6 to creep due to the pressure fluid being admitted through the pilot valve 4 to one side of the tilt control cylinder 5. This "dither" on the pilot valve also enables the control to respond to very small sustained variations in pressure in the pump and motor circuit. Alternatively, this "dither" may be effected hydraulically by introducing pulsations into the chamber 9.

To enable the pilot valve 4 to be centered accurately in its valve block when the links 31, 16 and 14 are in the neutral position the leaf spring 12 is fixed to a short cranked extension 61' of a lever 61 operated off an adjuster screw 62.

The position of the fulcrum 32 of the third mentioned, or lower end lever 31, i. e. of the lever 50 connected to the abutment of the spring 35 of the pressure measuring device, is adjustable so that the movement of the pilot valve 4 for a given variation in pressure due to the load reaction to the hydraulic motor 109' circuit can be varied 55 on test to ascertain the most suitable rate of response of angle of the lever 111', i. e. of tilt. In this connection such fulcrum, which as aforesaid is between the ends of this lever, is connected by a bracket 34' and a push-pull rod 32a to a remote control adjustor 52, this adjuster thereby adjusting the position of the fulcrum 32 of the lever 31 which connects the piston 36 to the aforesaid stabilising device.

The aforesaid double piston type of valve 29 of the stabilising device has its rod 38 prolonged into the inner or sliding block of the stabilising device to carry at its end remote from the double piston type valve a further similar type of valve 53. In operation the aforesaid gear pump 41 supplies the bores 28 and 25' of the two double piston type valves 29 and 25 respectively with fluid at a constant pressure, the fluid passing through the first mentioned double piston valve bore 28 and a port 19' leading to the pocket 19 containing the diaphragm 18, from whence it

passes via the conduit 26 to the bore 25' of the double piston type valve 25 which is connected to the aforesaid dash-pot 22 in one end of the outer block of the stabilising device and from whence the fluid passes via outlet 27 to exhaust.

The double piston valve 29 connected to the upper end of the lower lever 31 of the first mentioned three levers and the double piston valve 53 in the sliding block are pre-set so that when the said three levers 14, 16 and 31 are in the neutral position the port 19' communicating with the said pocket 19 and the outlet port 27 in the outer block of the stabilising device are of the same area and half open as shown, consequently the pressure drop through each is the same. By this means the diaphragm in the pocket is initially deflected under a pressure of half the supply pressure.

Any movement of the aforesaid double piston type of valve 29 connected to the levers 16 and 31 changes the area of the port 19' leading to the pocket and at the same time opens two ports 54 and 55 in, and communicating with, opposite ends of a chamber 56 receiving the sliding block 21, these two ports being otherwise covered by the piston elements of the double piston valve in the sliding block as shown. The opening of either one of these two ports 54, 55 allows pressure fluid to act on the end of the sliding block communicating with the appropriate port, so that the block will then move in the same direction of movement as the valve until the two ports 54, 55 are closed and the outlet 27 in the outer block is the same area as the port 19' communicating with the diaphragm pocket 19. Owing to the aforesaid dash-pot 22 in one end of the outer block 20 controlling the speed of movement of the double piston valve piston 25 controlling the said exhaust 27, there is a time lag between the changing of the area of the port 19' communicating with the pocket 19 and the equating of the areas of this latter port 19' and the said outlet port 27. This time lag can be adjusted by means of a dash-pot adjuster comprising a screw actuated conical valve 57 establishing communication between the dash-pot 22 and a source of supply of fluid.

The foregoing describes the general arrangement of the control gear, and it will be appreciated that in operation when, e. g. as aforesaid, the apparatus is adapted to the winding, rolling or feeding of materials which are very susceptible to the influence of changes in tension, having regard to the fact that the variable rate spring 35 takes care of changes in tension build-up in the strip material, i. e. changes in load on the means driven by the hydraulic motor 109' (or 109), by responding to such changes so as to vary the setting of the lever 111', the effective horsepower input to the hydraulic motor 109' is maintained at a predetermined value depending upon the tension required in the material and its velocity, e. g. in the feeding of strip metal from rolls to a take-up drum.

To maintain the said pressure constant, any error in pressure is as already described, utilised to move the tilt of the plate of the motor 109' in such a direction as will restore the pressure to its predetermined value. The control comes into the category of a "first derivative of error control," i. e. the movement of said pilot valve 4 controlling the admission of pressure fluid to the cylinder 5, is proportional to the error plus a function of the rate of changes of error. For

example, let the error in the pressure be "P" then the input to the pilot valve will be

$$K \left(f(P) + f \left(\frac{dp}{dt} \right) \right) = \text{pressure error} =$$

rate of change of pressure error

The first portion of this expression is obtained by means of the pressure measuring device 36 which is set before starting to roll the strip, by means of the tension adjustment shaft 60, so that when the tension in the strip is set at the required value, the pressure in the pump and motor system balance against the said spring 35 whereby the said three levers 14, 16 and 31 are held in the in-line or neutral position, the pilot valve 4 is closed, and there is no movement of the tilt control piston 6. Any variation in this tension produces a variation in strip horsepower and in pressure in the motor circuit and consequently the said three levers move from the neutral position, the pilot valve 4 opens, and the tilt control piston 6 moves to adjust the speed of the motor. Variable rate springs can be used in order that a given $\pm$ variation in pressure between the pump and motor produces the maximum rate of change of the speed of the hydraulic motor and its associated drum.

The second portion of the expression

$$f \left(\frac{dp}{dt} \right)$$

is obtained from the aforesaid stabilising device.

It is assumed that the double piston valves 29 and 53 in the said bore of the outer block 20 and in the sliding block 21 are suddenly moved in the direction of the arrow A, there is a sudden reduction of the area of the port 19' leading to the diaphragm pocket 19, whereas the adjustment of the area of the said outlet port 27 is retarded. This will cause a greater pressure drop through the port 19' than through the outlet port 27, with a consequent reduction in pressure in the said pocket 19, and hence the diaphragm will push out the rod 17 connecting it to the intermediate one 16 of the three levers. A reversal of the movement of piston valves 29 and 53 will result in this rod 17 and lever 16 being pulled in.

This displacement of the rod 17 is proportional to the rate of change of error, since the pressure drop in the pocket is proportional to the difference in area of the pocket port 19' and outlet port 27 and the slower the movement of the double piston valve 28 the closer the double piston valve 25 connected to the sliding block 21 follows the valve 29, and the area of opening of the said exhaust port 27 follows the area of opening of the port 19' connecting with the pocket 19. Variations in response of the sliding block 21 can be effected by adjustment of the valve 57.

Arising out of the foregoing, as the area of the outlet port 27 approaches the area of the diaphragm pocket port 19', the pressure drop through the exhaust port 27 approaches the pressure through the diaphragm pocket 19' and consequently the displacement of the rod 17 connected to the diaphragm is gradually reduced until the area of the outlet port 27 equals the area of the diaphragm pocket port 19' whence the diaphragm is returned to its initial position.

Now assume that there is a rise in tension in the strip above the predetermined value. This will create a rise in pressure in the conduit 112' (or 112b) and the resultant movement of the piston 36 in the pressure measuring device will

be in a direction of the arrow B, the lever 31 turning about its fulcrum 32 and the coupled double piston valves 29, 53 of the stabilising device will move inwards. The intermediate lever 16 of the said three levers will consequently turn about the pivot 16' on the rod connected to the diaphragm, and the lower end pivot 14' of the upper lever 14 will move out. At the same time the diaphragm rod 17 will move out owing to a reduction of pressure in the said pocket as previously indicated, the intermediate lever 16 will pivot about its lower end 16a and its movement will be increased. This latter additional movement due to the movement of the diaphragm rod 17 is gradually removed as indicated in the preceding paragraph. The upper lever 14 of the three levers will pivot about its upper end 14a and the pilot valve 4 will open in the direction of the arrow C. Pressure fluid will then be admitted behind the tilt control piston 6 and the tilt of the motor plate will be increased and the speed of the winding drum reduced.

When the tilt control piston 6 moves, it will create a suction in its associated dash-pot 9, and the piston 11 therein acting against the leaf-spring 12, will be drawn further into the cylinder. The upper lever 14 will pivot about its lower end and the pilot valve 4 will begin to close. The suction created in this dash-pot 9 will draw fluid through the adjustable needle valve 10 of the dash-pot, and opposing the leaf spring 12 tends to close the valve 4 so that when the pressure in the main system is restored the rate of the piston 6 has been retarded and approaches its new position simultaneously with the restoration of the pressure in the system. This action is continuous while the tilt control piston 4 is moving, and tends to restrict the rate of change of tilt or acceleration of the drum, smoothing the operation of the control and reducing any tendency for the tilt lever 111' to overshoot the required position. The amount of restriction to the rate of change of tilt to give the most stable condition is obtained by means of the dash-pot adjuster 10.

If the pressure in the pump-motor circuit falls, a reversal of the above sequence of events takes place, until the pressure returns to the normal value and the said three coupled levers are again in their neutral positions.

When it is desired to regulate the take-up of the fed material in synchronism with the processing of the material in such manner that if the feed or processing stops, the material can be fed over or through a feeler in the form of a lever, and for a photo-electric cell device or other means for measuring catenary, and the lever, or its equivalent connected through the medium of a mechanical, hydraulic or electric linkage, so that the rise and fall of the lever, or the effect of the change of catenary, i. e. the displacement of the strip material relatively to the light source of a photo-electric cell is transmitted to the lever 31 instead of to the cylinder 37 and spring 35 to obtain a control of the hydraulic drive.

In the embodiment shown in Figure 3 the lever 31 is connected at its upper end to a piston 29b so that this piston moves at a velocity proportional to the rate of change of error, resulting in oil being pressed out of or drawn in via the adjustable orifice 70 giving a pressure in the port 74 depending upon the rate of displacement of the piston 29b and adjustment of area of the orifice 70, which pressure reacts on piston 18b in cylinder 72 against the appropriate one of a

pair of balanced springs 71 giving a movement to the rod 17 proportionate to this pressure. Thus the displacement of the piston 18b and lever point 16' therefore depend upon the velocity of the piston 29b. The broken line parts (Fig. 4) show the effect on the lever assembly, a term

$$\frac{dp}{dt}$$

being added into the system. The addition of this term, or this additive motion has a damping effect on the system.

The foregoing stabilising means is an appreciably simplified alternative to the stabilising means previously described, the unit being submerged in oil, so that when the error signal has a velocity to the right in the diagram oil is sucked into the cylinder 73 and the piston 18b moves to the left. By providing an adjustable orifice 70 the ratio between the deflection of the piston 18b and the velocity of the piston 29b can be regulated.

It will be appreciated that the present invention is applicable also to the automatic control in quantity output of a pump so as to obtain a uniform pressure in lines to a number of apparatus fed by the pump, and in which the number of apparatus in use at a time is subject to variations e. g. in a works or aircraft where one pump is common to a plurality of hydraulic fluid pressure actuated apparatus. In such an arrangement changes in the number of apparatus being fed by the pump will change the pressure in the pump discharge side unless provision is made to adjust, e. g. the stroke and consequently quantity output of the pump automatically according to the changes in reaction due to increase or decrease in number of apparatus being served. Hence, by controlling the pressure in the line 38 to the cylinder 37 via means responding to the reaction in the supply line from the pump, the necessary changes in quantity of fluid flowing per given unit of time from the pump can be effected so as to obtain constant pressure to the apparatus in use.

We claim:

1. A reversible rolling mill, comprising rolls for rolling the material, a power unit driving the rolls, a pair of hydraulic pumps, a prime mover driving said pumps, and a pair of variable stroke hydraulic motors, a closed hydraulic circuit across each pump and its associated motor in the form of a supply conduit and a return conduit across each pump and its associated motor, a pair of drums one driven by one of said motors and the other by the remaining motor, said drums each serving alternately to coil-off and coil-on the material being rolled, so that as one acts as a coiler-on, the other acts as a coiler-off and vice versa and the coiler-off drum transmits the tension in the material across it and the rolls to its motor to feed back part of the power generated to the said prime mover, means to change the direction of drive to said drums to reverse the direction of feed of the material between the rolls, fluid pressure actuated means to increase the stroke of the coiling-on drum motor as the coil diameter increases so as to increase the torque applied to said drum and to maintain a substantially constant horsepower in the motor driving said drum, a pair of hydraulic fluid pressure actuated drivers having a source of operative fluid pressure distinct from that in the aforesaid pump-motor circuits and connected to the stroke varying means of the two motors to positively actuate the stroke varying means both for

increasing and decreasing the motor stroke, a valve with each said driver controlling the flow of pressure fluid to its associated driver both as regards direction and effective pressure, means receiving a controlling signal from the supply conduit of each pump and motor regulating the position of each said valve to control the direction and extent of displacement of each said driver so as to give a motor stroke changing response to the reaction effect in the hydraulic circuit of the associated pump and motor due to the change in tension in the material being fed through the rolls and the change in build-up of the material being wound on the coiling-up drum and the reduction in material being coiled-off the other drum.

2. A rolling mill according to claim 1 including in addition a pump feeding a motor driving the rolls, the motor driving the rolling means having a normally fixed stroke, and means common to all of said pumps to adjust the pumps so that at least the two pumps driving the two drum motors can have the same hydraulic output, and the other pump will have a fixed output ratio with respect to the said latter two pumps.

3. A rolling mill according to claim 1 wherein each said hydraulically actuated driver is a rod with a piston sliding in a cylinder, said rod being connected at one end operatively to a stroke controller for the associated hydraulic motor, a valve being provided to control the admission of fluid pressure to said cylinder to control the direction and extent of operation of the piston rod, and means adapted to be pre-set to respond to a predetermined load on the motor and yieldingly opposing increase in load on the associated motor due to the reaction of the strip material, servo means receiving an operating signal from said

latter means and adapted to control the extent of displacement of said valve to complete the connection of the said cylinder to the source of hydraulic fluid pressure and thereby to maintain a substantially constant horsepower output of the associated motor due to the adjustment of the stroke controller, and a fluid pressure displaced member operatively connected to the valve and responding to rate of change of the load on the motor to introduce a compensating movement into the said valve means.

4. A rolling mill according to claim 1 wherein said means adapted to be pre-set to respond to a predetermined load on the motor is a spring loaded member displaceable against the influence of its spring by the influence of hydraulic pressure in the supply side of the associated motor, means being provided to vary the effective load of said spring.
